UNITED STATES PATENT OFFICE

2,452,948

COAXIAL CABLE

Louis H. Morin, Bronx, N. Y., assignor of one-half
to Davis Marinsky, Bronx, N. Y.

Application May 13, 1944, Serial No. 535,405

4 Claims. (Cl. 174—27)

1

This invention relates to what is commonly referred to as coaxial cable. More particularly, the invention deals with conductors of this type and kind employing disc-type insulators spaced longitudinally of the conductor strand and arranged at an angle of inclination or skew on the conductors in order to distribute the outer peripheral surfaces of the discs throughout a greater length of the area of the outer conductor, as well as upon the inner conductor of the cable. The novel features of the invention will be best understood from the following description when taken together with the accompanying drawings, in which certain embodiments of the invention are disclosed and in which the separate parts are designated by suitable reference characters in each of the views, and in which:

Fig. 1 is a diagrammatic side and sectional view showing one arrangement of insulators which I employ.

Fig. 2 is a section on the line 2—2 of Fig. 1.

Figs. 3 and 4 are views similar to Fig. 1 showing other adaptations of my invention; and

Fig. 5 is a section on the line 5—5 of Fig. 4.

In the diagrammatic illustrations shown in the accompanying drawing, I have not illustrated a completely formed cable, but have simplified the showing to such parts of the resulting cable with which my invention is specifically concerned, namely the inner conductor, upon which the insulators are arranged and part of the outer conductor or enveloping jacket is also shown.

My invention deals primarily with the formation of the die cast insulators upon the inner conductor, for example, plastic die castings, such as of polyethylene, which may be cast two or more at a time directly upon the conductor and thereafter the outer conductor or jacket is mounted upon the insulators.

In Fig. 1 of the drawing, 10 represents the inner conductor, upon which are arranged at spaced intervals insulators 11 in the form of discs cast on the conductor 10 at an inclination to a perpendicular to the axis of the conductor or in what might be called a skewed position or an oblique position. It will thus be seen that the part 12 of the discs arranged directly upon the conductor 10 have, with a given thickness of disc, a greater surface contact with the conductor than would be the case if the discs were arranged perpendicularly to the axis of the conductor and, further, the discs spread over a longitudinal area of the conductor a distance greater than twice the thickness of the discs. It will also appear that the outer surfaces 13 of the discs are parallel to the

2

axis of the conductor 10 to fit in the bore of the outer tubular conductor or jacket 14. The surfaces 13 spread over a longitudinal area of the bore of the conductor 14 a distance many times greater than the thickness of the insulators. Also, the widthwise distance of contact of the discs at the surfaces 13 with the conductor 14 is greater than the thickness of the discs.

This construction permits a greater spacing of 10 the discs, one from the other, than would be possible with discs arranged perpendicularly to the conductor axis and, at the same time, provides, between the spaced discs, the desired air space. Still further, it will be apparent that the extremity of a disc, at one side of the conductor, overlaps the other extremity of an adjacent disc at the other side of the conductor, thus establishing a greater longitudinal distribution of the insulator bodies throughout the conductor.

20 The structure of Fig. 3 of the drawing differs from that shown in Fig. 1 in arranging converging insulators 15 and 16 at spaced intervals along an inner conductor 17 in such a manner that each pair of insulators 15 and 16 is arranged in the

25 same manner upon the conductor and the insulator 15 of one pair converges with the insulator 16 of an adjacent pair, as at 18, so that a resulting zig-zag arrangement of the insulators is provided throughout the full length of the conductor.

30 The insulators 15 and 16 have outer surfaces 19 parallel to the axis of the conductor 17 and which fit in the bore of an outer conductor or jacket 20. With the construction shown in Fig. 3, a wide spacing is provided between the ends 21 and 22 of the insulators 15 and 16 and a corresponding spacing is provided between the ends 23 and 24 of the insulators 15 and 16 of adjacent pairs. This construction does not pro-

35 vide the overlapping of the insulators, as seen in Fig. 1 of the drawing. However, the insulators do spread themselves throughout the major portion of the length of the outer conductor 20 and would provide a more firm and rigid cable

40 than would be the case with the structure shown in Fig. 1, which cable would be flexible in use.

In Figs. 4 and 5 of the drawing is shown another modification of the structure shown in Fig. 1; wherein insulators 25 are arranged at a greater angle of inclination and, further, are cast directly upon a pair of parallel conductors 26 and 27 to be mounted in an outer conductor or jacket 28, otherwise the structure of Figs. 4 and 5 is the same as that shown in Figs. 1 and 2.

55 Having fully described my invention, what I

claim as new and desire to secure by Letters Patent is:

1. In flexible coaxial cable comprising an inner conductor and a tubular conductor enveloping the inner conductor in spaced relation thereto, the combination therewith of die cast insulators on the inner conductor spaced longitudinally thereof and adapted to position said inner conductor within said tubular conductor, said insulators comprising discs arranged at an inclination to said inner conductor, each disc being parallel to adjacent discs, the extremity of each disc at one inner side of the tubular conductor being in overlapping relation to the extremity of an adjacent disc at the opposite inner side of said tubular conductor.

2. In flexible coaxial cable comprising an inner conductor and a tubular conductor enveloping the inner conductor in spaced relation thereto, the combination therewith of insulators on the inner conductor spaced longitudinally thereof and adapted to position said inner conductor within said tubular conductor, said insulators comprising discs arranged at an inclination to said inner conductor, opposed surfaces of adjacent discs being parallel, the extremity of each disc at one inner side of the tubular conductor being in overlapping relation to the extremity of an adjacent disc at the opposite inner side of said tubular conductor.

3. In flexible coaxial cable comprising a pair of inner conductors and a tubular jacket in spaced relation thereto, the combination therewith of die cast insulators on the inner conductors spaced longitudinally thereof and adapted to position said inner conductors within said tubular jacket, said insulators comprising discs arranged at an inclination to said inner conductor, each disc be-

ing parallel to adjacent discs, the extremity of each disc at one inner side of the tubular conductor being in overlapping relation to the other extremity of an adjacent disc at the opposite inner side of said tubular conductor.

5 4. In flexible coaxial cable comprising a pair of inner conductors and a tubular jacket in spaced relation thereto, the combination therewith of insulators on the inner conductors spaced longitudinally thereof and adapted to position said inner conductors within said tubular jacket, said insulators comprising discs arranged at an inclination to said inner conductor, each disc being parallel to adjacent discs, the extremity of each disc at one inner side of the tubular conductor being in overlapping relation to the other extremity of an adjacent disc at the opposite inner side of said tubular conductor.
